UNITED STATES PATENT OFFICE.

ORLANDO R. ERWIN, OF FOREST HILLS, NEW YORK, ASSIGNOR TO FOAMITE-CHILDS CORPORATION, OF NEW YORK, N. Y., A CORPORATION OF DELAWARE.

FIRE-EXTINGUISHING APPARATUS.

Application filed July 24, 1920. Serial No. 398,653.

This invention relates to foam-type fire extinguishing apparatus and consists in improved means for conjointly controlling the flow and mixing of the foam-making solutions and their discharge as a foam-mixture, being herein exemplified as applied to a so-called sprinkler head but without limitations to such type of devices.

In the accompanying drawings:

10 Figure 1 is a view in side elevation of a sprinkler head fire extinguishing apparatus embodying my invention and forming one unit of a fire extinguishing system.

Figure 2 is an end view thereof.

15 Figure 3 is a view, partly in elevation and partly in vertical section, showing my novel form of sprinkler head.

Figure 4 is a horizontal cross sectional view taken on a line 4-4 of Figure 3.

20 Figure 5 is a similar view taken on the line 5-5 of Figure 3.

Figure 6 is a view in side elevation of a modified form of sprinkler head, and showing two of the heads located along the 25 pipe lines of the system.

Figure 7 is a vertical longitudinal sectional view taken through one of the forms of sprinkler head shown in Figure 6, and illustrating particularly the interior construction of the head for obtaining a uniform mixture and distribution of the incoming and outgoing solutions.

Figure 8 is a cross sectional view taken 30 on the line 8-8 of Figure 7.

35 Referring now to the accompanying drawings in detail, and particularly Figures 1 to 5 inclusive, the letter A indicates a ceiling or other support from which is suspended a hanger B supporting the solution 40 conducting pipes C and D. Normally each solution is stored separately each in its reservoir (not shown), and from the reservoirs the solutions pass into the respective pipes provided for conducting purposes. The apparatus may be operated upon either the 45

“wet pipe” system or the “dry pipe” system. In the “wet pipe” system the pipes are filled with the solution clear up to the sprinkler heads and maintained under pressure until the time of operation, for instance the occurrence of a fire which fuses the link of the sprinkler head, when the valve will be opened in the mixing cham-

ber or head and the two solutions will be commingled and forced out from the head 55 under pressure, forming the foam. In the “dry pipe” system the solutions are maintained in the separate reservoirs and the pipes are filled with compressed air until the link of the sprinkler head fuses, thus 60 causing the valves of the head to open, thereby permitting the escape of the air from the pipes and allowing the solutions to flow into the head where they are mixed, and generate foam which is discharged upon the 65 fire.

In Figures 1 to 5 the sprinkler head which is indicated as an entirety by the letter E is shown as connected with the T-union F in the pipe C, the threaded shank 1 of the mixing chamber 2 of the sprinkler head being threaded into the union. It will of course be understood that a system of the pipes C and D may be run wherever needed through a building or other structure, and that there may be employed as many sprinkler stations each equipped with one of the sprinkler heads E as may be required.

While each sprinkler head is in direct communication with the solution pipe C as just described, it is also connected through a branch G with the pipe D, the branch pipe G being secured by means of a nut 3 upon the threaded shank 4 of the chamber 2, said shank merging at its inner end in the solution inlet 5 emptying into the chamber to one side of the latter or at a tangent as is best shown in Figures 3 and 5. The solution from the pipe D therefore enters the chamber 2 through the inlet 5, just as the solution from the pipe C is designed 70 to pass through the tubular threaded shank 1 to its inlet 6 leading into the chamber 2, in the present instance one solution entering the chamber horizontally while the other solution enters vertically. However, when the apparatus is not in operation the solutions are maintained separated at the mixing head because over the inlet 6

75 I locate a diaphragm 7, preferably in the nature of a thin, springy, flexible sheet of metal such as copper-bronze, the center of said diaphragm having a port 8 formed therein which is surrounded by a seat or flange 9 of lead or other suitable material. This diaphragm 7 is locked in 80 85 90 95 100 105

place by means of a threaded ring 10, screwed into the wall of the lower portion of the chamber 2, said ring having spanner lugs 11. On top of this ring 10 is adapted to rest a thin circular disk 12, also of metal, and having a central port 13 therein. This disk 12 lies beneath and separates the inlet 5 from the inlet 6 as will be understood by reference to Figure 3; this disc may be omitted. Across the upper portion of the chamber 2 there extends the thin, flexible, metallic diaphragm 14 having a central port 15 surrounded by the valve seat or flange 16 of lead or other suitable material. This diaphragm 14 is locked in place by the screw ring 17 threaded into the upper end of the chamber 2, and extending upwardly from this ring 17 are the yoke-arms 18 converging in the block 19 carrying a suitable deflector crown 20, the function of which is to give direction to the emergent mixture.

The fusible link of the sprinkler head, which may be of any usual construction, and formed from a metallic alloy which melts at a relatively low temperature, is shown at H and is socketed at its upper end as at 21 beneath the head block 19, and at its lower end is seated as at 22 in the socket 23 formed in the head of the conical duplex valve I. This duplex valve in Figure 3 is shown as in the nature of a tapered plug, the top bead 24 of which normally seats on the seat 16 of the diaphragm 14, while the lower portion of the plug projects through the port 13 of the disk 12, and the terminal of the plug seats upon the seat 9, forming the valve seat on the diaphragm 7. Thus it will be noted that this duplex plug valve I acts to close the ports of the lower and upper valve seats, and also the port 13 of the diaphragm 12. Consequently under normally inoperative conditions, as when there is no fire and the fusible link H is intact, the solution from the pipe C is prevented entering the mixing chamber through the lower port 8, by means of the lower terminal of the plug valve, while the solution from the pipe G is prevented leaving the chamber by the upper end of the plug valve closing the port 15, the plug valve itself being maintained closed against the pressure in the pipes by means of the fusible link H. On the melting of the fusible link H however, as in case of fire, such link will of course break down thus releasing its holding action upon the duplex plug valve, and the pressure through the pipes C and G connected with the pipe D will blow the plug upward and outward, thus opening the ports and permitting the solution from the pipe C to enter the mixing chamber and there commingle with the solution from the pipe G, the mixed solutions then being forced by the pressure centrally upward and outward through the port 16 in the upper diaphragm 14, the mixture being blown upward and striking the deflector 20 as indicated in the dot-and-dash lines of Figure 3, will drop or be deposited upon the fire, or adjacent flooring or other point in the vicinity of the sprinkler head. The duplex plug valve may be formed of glass, or other non-corroding material, and likewise the seats upon which the valve rests are preferably formed of non-rusting material. In addition the thin resilient, flexible nature of the diaphragms carrying the valve seats enables both to make a proper closing contact with the valve when the latter is in position; it is important that the engagement of the valve with at least one of the seats be a resilient engagement, produced in this or some equivalent manner.

In Figures 1 to 5 I have shown the solution inlet 5 as entering the mixing chamber at a tangent or angle, but I wish it to be understood that this inlet may lead centrally and directly into the mixing chamber, as I have found both arrangements to be advantageous.

In Figures 6 to 8 inclusive, I have shown a modified form of my invention. In this instance I have dispensed with the use of the branch between the two solution-conducting pipes, and have made the chamber of the mixing head of sufficient size to bridge the two pipes and to perform the necessary functions. Furthermore in the case of this modification I have provided the interior of the mixing chamber of the sprinkler head with an arrangement of baffle walls and ports to guide and direct the two solutions along such paths that they will be more thoroughly mixed while converging at or toward the center of the chamber.

The letter C' indicates one solution conducting pipe and D' is the second solution conducting pipe. In Figure 6 I have shown two sprinkler heads in the piping system, one being arranged intermediate the lengths of the pipes and the other constituting a terminal sprinkler head uniting the ends of the pipes. The enlarged view in Figure 7 is taken through the intermediate sprinkler head, but the construction of all of the heads is substantially the same.

It embodies a mixing chamber indicated as an entirety by the letter E' and including a body section 2' the lower end of which is connected through a tubular shank in communication with the pipe D', said shank being indicated by the numeral 1'. At the lower end of this mixing chamber is a thin flexible metal diaphragm 7' having a valve seat 9' surrounding the central port 8'. Normally resting upon and closing this valve seat is the lower terminal of the duplex valve I', said terminal being indicated at 2'. The stem of the duplex valve I' extends through alining bores 25 in the baffle grid 130

or spider J, the upper end of said stem carrying a valve head 2 which normally closes the port 15' located centrally of the upper diaphragm 14'. This upper dia-
5 phragm 14' is locked in position by a threaded ring 17' from which extends the up-
wardly projecting yoke-arms 18' of the sprinkler head, these arms terminating in the block 19' carrying the deflector 20'. The
10 fusible link H' when in normal inoperative position holds the duplex valve seated to close the port 8' and 15'. The solution con-
ducting pipe C' leads straight in to the mix-
ing chamber, the inlet of said pipe shown at 5' being at right angles to the inlet 6', through
15 which the solution from the pipe D' enters the mixing chamber. As the solution passes into the mixing chamber from the pipe C' through the inlet 5' it will pass around the
20 circular wall 26 of the grid or baffle, and up through the ports or openings 27 formed in the top horizontal wall 28 of the grid or baffle and thus pass into that portion of the chamber lying directly beneath the
25 upper diaphragm 14'. However, the solution passing from the solution pipe D' through the inlet 6' will, when the duplex valve is open, pass through the port 8', up through the lower portion of the mixing
30 chamber and be thence directed inward toward the center of the chamber by the annular shoulder 30 of the lower wall 31 of the grid or baffle, and will escape up through the central ports 32 and 33 of the grid and
35 mix with the solution of the pipes C' in the upper portion of the chamber and directly beneath the diaphragm 14', the mixed solu-
tions leaving the mixing chamber in a central stream through the port 15'. It will
40 further be understood that I do not confine myself to the precise arrangement of parts as shown herein, nor to the particular type of duplex valves employed for controlling the ports at the valve seats.

45 What I claim is:

1. A fire extinguishing apparatus comprising a discharge head including a mixing chamber having two independent inlets for the two different components of a foam pro-
50 ducing fire extinguishing mixture, and hav-
ing an outlet for said mixture and a valve means normally holding the components in separated condition and normally closing the outlet rendered active under fire conditions for controlling the flow of said components into said chamber and the exit of the mixture therefrom.

2. In a discharge head for fire extinguishing apparatus, a mixing chamber having separate inlets for different solutions which when mixed will form a fire extinguishing foam, said mixing chamber also having an outlet for the mixed solutions, a valve for closing one of the inlets and the outlet, and a fusible member normally holding said valve

in closed position and adapted when fused to permit the opening of the valve and the escape of the mixture from the chamber.

3. In a discharge head for fire extinguishing apparatus, a solution mixing chamber 70 having two inlets and an outlet, said inlets being arranged at an angle relative to each other, valve means controlling one of said inlets and the outlet and means normally holding said valve means in closed position 75 and adapted under certain conditions of temperature to permit the opening of said valve means.

4. A fire extinguishing apparatus comprising a discharge head including a solution 80 mixing chamber, means for independently introducing foam-forming solutions into the mixing chamber, said chamber having an outlet for the mixed foam-forming solutions, and unitary means operating automatically 85 under certain conditions of temperature to allow the mixing of the solutions in the mixing chamber and the flow of said mixed solutions through the outlet of the chamber.

5. A fire extinguishing apparatus comprising a discharge head including a mixing chamber and an automatic valve member, means for separately introducing foam-forming solutions into the mixing chamber where they are mixed, said chamber having 90 an outlet for the mixed solutions and mechanical means located within the chamber for assisting in mixing the solutions and directing such solutions through the outlet. 95

6. In a discharge head for fire extinguishing apparatus, a mixing chamber having diaphragms forming walls for the chamber and provided with ports, a solution conduit leading into the mixing chamber between said diaphragms, a second solution conduit 100 terminating outside of one of the dia-
phragms but communicating with the mix-
ing chamber through the port of such dia-
phragm, a valve normally closing the ports and a member normally holding said valve 105 in port-closing position and adapted to per-
mit the release of the valve thereby opening the ports and allowing the solutions to mix within the mixing chamber and to leave said mixing chamber through one of the ports in 110 foam generating condition.

7. A fire extinguishing apparatus comprising a discharge head including a solution mixing chamber, means for causing ad-
mission of foam-forming solutions into the 115 chamber and discharge of mixed solutions therefrom, comprising two valve seats and a common valve device therefor, and means located within the chamber for assisting in mixing the solutions within the chamber. 120

8. A fire extinguishing apparatus comprising a discharge head including a solution mixing chamber and a valve, means for in-
troducing foam-forming solutions into the 125 chamber, an outlet for the exit of the mixed 130

- solutions from the chamber, and a baffle located within the chamber for assisting in mixing the solutions and for directing the flow of the same through the chamber to the outlet.
9. A fire extinguishing apparatus comprising a discharge head including a solution mixing chamber having an automatic valve member, means for introducing foam-forming solutions into the chamber, said chamber having an outlet for the exit of the mixed solutions, and a grid-like baffle member located within the chamber for assisting in mixing the solutions.
10. In a discharge head for fire extinguishing apparatus, a mixing chamber including a pair of spaced diaphragms forming end walls of the chamber, each of said diaphragms having a port therein, a solution conducting member communicating with the interior of the mixing chamber, a second solution conducting member terminating at the exterior of one of the diaphragms but communicating through the port of the latter with the mixing chamber, a valve device normally closing the ports of the diaphragms, fusible means for maintaining the valve device in closed position, and adapted when fused to release the valve and permit the two solutions to mix in the mixing chamber and to leave through one of the ports in foam-forming condition, and a grid-like baffle member within the mixing chamber for assisting in mixing the solutions.
11. A fire extinguishing apparatus comprising a discharge head including a solution mixing chamber having thermally controlled means of inlet and exit for the solutions and a grid-like baffle member for assisting in mixing the solutions and directing the flow of the latter through the chamber to the outlet.
12. A fire extinguishing apparatus comprising a discharge head including a solution mixing chamber, means for independently introducing foam-forming solutions into the mixing chamber, said chamber having an outlet for the mixed foam-forming solutions, a deflector surmounting said mixing chamber to distribute the mixture outwardly in all directions from the chamber, and valve means operating automatically under certain conditions of temperature to allow the mixing of the solutions in the mixing chamber and the discharge of said mixed solutions through the outlet of the chamber and against said deflector.
13. A fire extinguishing apparatus comprising a discharge head including a mixing chamber having independent inlets for the different components of a foam producing fire extinguishing mixture and an outlet for said mixture, mechanical means located within the chamber for assisting in mixing the solutions and directing such solutions through the outlet, and valve means rendered active under certain conditions of temperature for controlling the flow of said components into said chamber and the exit of the mixture therefrom.
14. A fire extinguishing apparatus comprising a discharge head including a solution mixing chamber having suitable means of inlet and exit for the solutions, valve means rendered active under certain conditions of temperature for controlling the flow of component solutions through the inlets and the discharge of the mixture through the exit, and a grid-like baffle member for assisting in mixing the solutions and directing the flow of the mixture through the chamber to the exit thereof.
15. In apparatus of the class described, a mixing chamber with a plurality of inlets, a common outlet, a common valve controlling the discharge through the outlet and the flow through one inlet, and a fusible member normally holding the valve in closed position.
16. In apparatus of the class described, a mixing chamber having at one end an inlet and intermediate its ends a second inlet, said inlets for solutions foaming when mixed, the ends of the casing of thin flexible material ported for the inlet of the one solution at the inlet end and for the outlet of the mixture at the other end, a common valve controlling the ports, and a fusible member normally holding the valve closed, said flexible ends adapted to positively unseat and discharge the valve when sprung under the pressure of the expanding mixture.
17. In foam fire-extinguishing apparatus, the combination of a casing containing a chamber to which foam-making solutions are admitted and in which they are brought into contact, two valve ports for said chamber, a common valve member for closing said ports, said member having resilient seating engagement with one of said ports and means for holding said valve in closed position.
18. A fire extinguishing apparatus comprising a discharge head including a solution mixing chamber having two inlets and an outlet, valve means controlling one of said inlets and the outlet, and means normally holding said valve means in closed position and adapted under certain conditions of temperature to permit the opening of the valve means.
19. In a discharge head for fire extinguishing apparatus, a solution mixing chamber having two inlets and an outlet, one of said inlets being arranged in substantial alignment with the outlet, valve means controlling the alining inlet and outlet, and means normally holding said valve means in closed position and adapted under cer-

tain conditions of temperature to permit the opening of the valve means.

20. A fire extinguishing apparatus comprising a discharge head including a mixing chamber having independent inlets for different fluids and an outlet for said mixture, a deflector surmounting the said mixing chamber, valve means for said mixing chamber operative for normally holding the said fluids in separated condition and for controlling the discharge of the mixture from

the chamber and a fusible member between the valve means and the said deflector normally holding said valve means in closed position and adapted when fused to permit ¹⁵ the opening of the valve means for effecting intermixture of the fluids and the discharge of the mixture from the mixing chamber.

Signed at New York city, in the county of New York, and State of New York, this ²⁰ 19th day of July A. D. 1920.

ORLANDO R. ERWIN.
